UNITED STATES PATENT OFFICE.

LEON L. KAISER, OF IMLAY, NEVADA.

SAW-SET.

1,334,905.

Specification of Letters Patent. Patented Mar. 23, 1920.

Application filed June 24, 1919. Serial No. 306,286.

To all whom it may concern:

Be it known that I, LEON L. KAISER, a citizen of the United States, residing at Imlay, in the county of Humboldt and State 5 of Nevada, have invented new and useful Improvements in Saw-Sets, of which the following is a specification.

This invention has reference to an improved construction of saw sets, and has for 10 its primary object to simplify and improve the existing art by producing a device of this character which shall be of an extremely simple nature, embodying a combination and operative arrangement of parts 15 wherein circular saws of different widths may be set in an easy and expeditious manner.

Other objects and advantages will present 20 themselves as the nature of the invention is better understood, reference being had to the accompanying drawings, in which:

Figure 1 is a side elevation of the improvement.

Fig. 2 is a top plan view thereof.

Fig. 3 is a sectional view approximately 25 on the line 3—3 of Fig. 2.

Fig. 4 is a sectional view approximately on the line 4—4 of Fig. 1.

From experience I have found that a successful saw set may be made from a piece of 30 railway rail by beveling the head at one of the ends thereof and by arranging thereon a bracket carrying the setting tool, but, of course, I do not wish to restrict my improvement 35 to the employment of railway rails.

In the drawings the numeral 1 designates 40 a steel I-beam which, as previously stated, is preferably in the nature of a piece of railway rail. The head 2 of the beam or rail, at one of the ends thereof is beveled downwardly and outwardly as at 3, and to the web of the rail, at the said beveled end I secure one arm 4 of a bracket member. The arm 4 is preferably connected to the web 45 by bolts and nuts, and is extended outward of the rail end and bent upon itself or otherwise formed to provide two horizontally disposed connected arms 5 and 6 respectively. The connecting element between 50 the arms is preferably rounded, and the connecting element between the arms 4 and 5 is preferably likewise rounded. This last mentioned connection, indicated for distinction by the numeral 7 is given a half twist 55 so that the arms 5 and 6, while arranged parallel to each other are disposed at an

angle similar to that of the beveled end 3 of the rail 1. The arms 5 and 6 are provided with registering openings through which passes the shank 9 of the setting member 10. The outer end of the member 10 is headed as at 11 and the lower end thereof is disposed directly over the beveled end 3 of the rail. Passing through the shank 9 is a stop element in the nature of a 60 cotter pin 12, and surrounding said shank and exerting a pressure between the lower arm 5 and the cotter pin is a helical spring 13. The spring normally retains the operative end of the setting element above the 65 seat provided with the beveled end 3 of the rail.

The head of the rail, at a suitable distance from the seat 3 is provided with a plurality of spaced round openings 14, and the said 70 head of the rail, from one of the sides thereof is provided with transverse threaded openings 15 which enter one each of the openings 14. In one of the openings 14 is screwed the threaded shank of a headed element 16, and this member 16 is designed to contact with the rounded stud or shank 17' which is eccentrically secured to a round headed member 17. The headed member 17 provides a pivot for the hole in the center 75 of the saw, so when the saw is rotated on same each tooth is brought directly under setting member 10, and by turning said member 17 the saw may be adjusted toward or away from the seat 3 thereby giving more 80 or less set as desired. The holes 14 are so spaced that saws of various sizes may be set with the improvement. Band saws and other saws of uniform width may be readily 85 set with this arrangement and by removing member 17 saws with tapering backs may 90 also be set.

It is thought, from the foregoing description, when taken in connection with the drawings, the simplicity of the construction 100 and the advantages thereof will be readily apparent without further detailed description.

Having thus described the invention, what is claimed as new, is:

1. In a saw set, a body member having a 105 beveled end, an S-shaped bracket having a lower straight angle extension which is secured to the member to arrange its intermediate and outer arms parallel with each other and with the beveled end of the body member, a headed set member having a

shank passing through the intermediate and outer arms of the bracket, spring means between said arms co-engaging with the shank to hold the latter normally in one position 5 on the bracket, and an eccentrically mounted stop on the outer surface of the body member.

2. A saw set comprising a steel I-beam having the head thereof at one of its ends 10 beveled to provide a seat, a bracket including an arm secured to the web of the I-beam and including upper and lower connected arms arranged parallel to each other and parallel to the seat, said upper arms having 15 spaced openings therethrough, a headed set member having its shank passing through

the openings, a stop on the shank of the said member below the upper arm of the bracket, a spring on the said shank contacting with the stop and with the lower arm for raising 20 the set above the seat, the head of the angle member having vertically spaced openings therein and transverse headed openings communicating with the vertical openings, a stop including a round head having an eccentric shank thereon designed to be received in one of the openings, and a binding element passing through one of the transverse openings and contacting with said shank. 25

In testimony whereof I affix my signature.
LEON L. KAISER. 30
